UNITED STATES PATENT OFFICE.

JULIUS WACHHOLZ AND WILLIAM BEHRENS, OF ST. LOUIS, MISSOURI.

TRANSOM-PLATE FOR WAGONS.

SPECIFICATION forming part of Letters Patent No. 341,707, dated May 11, 1886.

Application filed November 23, 1885. Serial No. 183,693. (No model.)

To all whom it may concern:

Be it known that we, JULIUS WACHHOLZ and WILLIAM BEHRENS, both of the city of St. Louis, in the State of Missouri, have invented a certain new and useful Improvement in Transom-Plates for Wagons, of which the following is a full, clear, and exact description, reference being had to the accompanying drawings, forming part of this specification.

Figure 1 is a front elevation of a fore axle and bolster, the hounds being in transverse section. Fig. 2 is an enlarged section transverse to the axle at 2 2, Fig. 1. Fig. 3 is an under perspective view of the upper transom-plate. Fig. 4 is a perspective view of the under transom-plate. Fig. 5 is a longitudinal section of the transom-plates on a much larger scale, the same being shown in connection with a king-bolt, and the upper transom-plate being tilted on the lower transom-plate.

Our improvement consists in the described construction of the bearing-faces of the two plates.

A is the axle, B the hounds, and C the lower bolster, which is fast to the axle.

D is the upper bolster, upon which the fore end of the wagon-body is directly supported.

E is the lower transom-plate, which is secured to the under bolster or axle timber by means of bolts F, whose heads may be countersunk in the plate, if desired.

e are lips or snugs upon each side, which take over the edges of bolster C. The bearing-face of the plate E has a central boss, e', centrally bored to receive the king-bolt G.

e² and e³ are annular ribs upon the plate concentric with the boss e', and fitting in corresponding annular grooves of the upper transom-plate, H. The plate H has a central bore,

h⁴, fitting the frusto-conical boss e', and has annular ribs h h', entering the annular grooves between the ribs e² e³, and, locking with the said latter ribs, relieve the boss e' and the king-bolt from severe side strain, and also to prevent the entrance of dust between the bearing-faces and prevent the escape of oil or grease from the bearing.

I is an oil-hole.

We are aware that transom-plates have been

made with a central boss upon the lower plate 50 and a single annular rib upon each plate; but it has been found that the grease or oil cannot be retained in the bearings of this construction, and that the king-bolt is subjected to such severe strains as to soon wear loose and to be 55 broken. It will be seen that the periphery h² of the bearing-face of the upper transom-plate covers the top of the under bearing-rib, e', so that there is no place for the lodgment of dirt. If the strain comes from any direction, 60 it will be seen that there are four places against which the side pressure comes, each of the ribs h h' having two places of side bearing on the boss and ribs e² e³, and thus the strain is distributed. The upper plate, H, 65 has lips h³, taking over the edges of the bolster D, and is bolted or screwed to this bolster.

By referring to Fig. 5, which shows the action of the plates, it will be seen that the fulcrum-point 1, on which the upper plate tilts 70 up, is at the outer one, e³, of the standing flanges on the lower plate, so that however much the upper plate may be tilted it is restrained from side movement, and consequently as the upper transom-plate descends it must 75 drop into its proper position. The extra annular rib e² prevents the escape of oil, as it is a standing instead of a descending flange, as heretofore constructed.

We claim—

1. The combination of a transom-plate formed with a boss, e', inner rib, e², and outer rib, e³, and another transom-plate having a central bore, h⁴, receiving the boss, inner rib, h, and outer rib, h', entering the grooves between the first-named ribs, and bearing-face h² over the first-named outer rib, substantially as set forth.

2. The combination of lower transom-plate, E, having bored boss e' and ribs e² e³, and the upper transom-plate, H, having ribs h h', and the lips upon both plates taking over the edges of the bolsters, substantially as set forth.

JULIUS WACHHOLZ.
WILLIAM BEHRENS.

In presence of—

EDWARD S. KNIGHT,
JOSEPH WAHLE.
